UNITED STATES PATENT OFFICE.

LOUIS WULKAN, OF LAWRENCE, NEW YORK.

DESIGN FOR A DISPLAY-STAND.

52,374.

Specification for Design. Patented Aug. 27, 1918.

Application filed May 17, 1918. Serial No. 235,199. Term of patent 3½ years.

To all whom it may concern:

Be it known that I, LOUIS WULKAN, a citizen of the United States, and resident of Lawrence, Nassau county, State of New York, have invented a new, original, and ornamental Design for a Display-Stand, of which the following is a specification, reference being had to the accompanying drawing, forming a part thereof.

In the drawings I have shown in elevation a representation of a display stand embodying my design.

The design comprises a display stand of ornamental construction having a number of shelves each provided with an ornamental rail around the periphery thereof, said shelves being positioned one over the other and carried by a central support provided with a suitable base, substantially as shown in the drawings.

I claim:

The ornamental design for a display stand as shown and described.

LOUIS WULKAN.
